Primary Examiner — Shawn T Gingrich*Assistant Examiner* — Katherine E Morris(74) *Attorney, Agent, or Firm* — Rotek Law; Cristian Andres Rodriguez(57) **CLAIM**

The ornamental design for a lotion soap dispenser as shown and described.

DESCRIPTION

FIG. 1 is a perspective view of a lotion soap dispenser showing my new design;

FIG. 2 is a front view thereof;

FIG. 3 is a back view thereof;

FIG. 4 is a left view thereof;

FIG. 5 is a right view thereof;

FIG. 6 is a top plan view thereof; and,

FIG. 7 is a bottom plan view thereof.

The broken lines depict portions of the lotion soap dispenser and form no part of the claimed design.
